(57) CLAIM

The ornamental design for a projector light, as shown and described.

DESCRIPTION

FIG. 1 is a perspective view of the projector head with yoke and stake attached.

FIG. 2 is a right side view of FIG. 1 thereof.

FIG. 3 is a left side view of FIG. 1 thereof.

FIG. 4 is a front view of FIG. 1 thereof.

FIG. 5 is a rear view of FIG. 1 thereof.

FIG. 6 is a top view of FIG. 1 thereof; and,

FIG. 7 is a bottom view of FIG. 1 thereof.

The broken line disclosure represents portions of the projector light which form no part of the claimed design.
